[57] CLAIM

The ornamental design for a cleat skirt, as shown and described.

DESCRIPTION

FIG. 1 is a perspective view from below of a cleat skirt showing our new design;

FIG. 2 is a perspective view from above of the cleat skirt shown in FIG. 1;

FIG. 3 is a perspective view from below of the cleat skirt shown in FIGS. 1 and 2 attached to a spike shown by dotted lines; and,

FIG. 4 is a perspective view from above of the cleat skirt shown in FIGS. 1 and 2 attached to a spike and a threaded member shown by dotted lines.

The broken lines showing the cleat spike and cleat screw are for illustrative purposes only and form no part of the claimed design.

FIG. 1

FIG. 2

FIG. 3

FIG. 4
